FERRULE MOUNTING

Lavon D. Miller, Hicksville, Ohio

Application November 30, 1938, Serial No. 243,079

1 Claim. (Cl. 144—309)

This invention relates to assembly of a sleeve on a woodlike handle.

This invention has utility more particularly when incorporated in tapered tubular ferrule into which may be inserted a wood handle which has been previously immersed in hot oil and the assembly then bent.

Referring to the drawing:

Fig. 1 is a side elevation, partly broken away, 10 of a wood handle hereunder;

Fig. 2 is a blank for a ferrule of sheet metal;

Fig. 3 is a view of the weld formed in the tapered tubular ferrule from the blank of Fig. 2;

Fig. 4 is a view of the wood handle of Fig. 1 15 previously dried and thus immersed for a hot bath;

Fig. 5 is a view of the assembly between the ferrule of Fig. 3 and the wood handle after the bath of Fig. 4;

Fig. 6 is a view of the press-formed or bend shaping of the combined ferrule and wood handle; and

Fig. 7 is a view, with parts broken away, of the formed or distorted combined ferrule and handle of Fig. 6 as adapted to carry a tool.

A cylindrical handle 1, as of fibrous material such as wood, is shown with a slight shoulder 2 and low degree of a taper portion 3 to a more abrupt taper portion 4 toward a tool end terminal 5. A blank 6 is shown with slightly converging sides 7 to more abruptly converging sides 8 thence, to a short width portion 9. This blank (Fig. 2) is formed into a tubular ferrule 10 having a weld 11 continuous along one side thereof through a major taper portion 12 to a small terminus 13. Remote from this terminus 13 is the less degree taper portion 14 in this completed tubular ferrule.

Burner 15 may be effective under a vessel 16 containing a liquid 17, thereby to provide a bath in which the reduced portions of the handle 1 may be immersed from the small end 5 to or slightly above the shoulder 2. This immersion is at a temperature for effective penetration of the heat thinned liquid, whether such be paraffin wax of 146° melting point, crude paraffin, petrolatum, linseed oil, or straw oil. The purpose is that the enveloping of the heated wood in the liquid has a tendency against open pore result therefrom. This coating material is such as may not penetrate the walls of the cellular structure of the fibrous material to expand, but is so thinned as to provide an effective coating for the cells and general structure. With such treatment as against harshness of exposure to

the air, it is found there is retained the life values for flexing, bending, and against fracture comparable to, if not exceeding, that of approximately green wood fiber. Inasmuch as the wood is kiln dried or thoroughly seasoned before this bath, this means that there is not moisture disturbance factor for introducing warping or shrinking problems. Accordingly, as this immersion is effective to be the equivalent of penetration for heat, if not for the thin liquid at the 10 temperature of say 250° to 350° F., the reduced portion may be removed from the bath, and have the formed ferrule (Fig. 3) thrust thereon in the assembly of Fig. 5.

Such straight assembly may be distorted by 15 placing such unit on a die member 18 to be opposed by a complementary die member 19 in a press. This placing is preferably with the weld 11 along the concave or non-stretch receiving side. Resultantly therefrom, a bend 20 is imparted to the more reduced portion in adapting the structure as a tool handle to receive a tang 21 from a tool 22 inserted to a shoulder 23 to close the small end 13 of this ferrule as in the bent handle. The tool may be a shovel, spade, 25 fork, or other type of hand device. The distortion of the wood handle in conjunction with the non-heated ferrule as occurring at the taper with the heated wood or filler, is effected by first driving the snug fitting ferrule into position on 30 the handle for the larger end of the ferrule to abut the shoulder 2. Notwithstanding the heating of the wood by immersion in a hot oil bath, there is no resultant shrinkage. The oil is to an extent a lubricant to permit ready thrusting of the ferrule into position.

The method of treatment, which includes immersing the wood in the hot oil, effects sufficient filling of the cells of the wood with the oil that the wood is strengthened toward retaining its original properties against collapse. In practice, there is thus imparted a toughness against fracture, even to the extent that the wood may experience a change of form or "give" when subjected to excessive strain, and after such strain be removed, has resiliency to spring back therefrom to its prior form.

While the treatment hereinbefore considered has had to do with wood as air dried or kiln dried and the avoidance of tendency to fracture by maintaining the walls resilient due to the oil coating, experience herein goes further. In fact, unseasoned or green wood may be subjected to the bath herein with avoidance of shrinkage problems therefrom. This may mean that there is 55

an effective cell coating or displacement of superficial moisture or the volatiles of the wood or effective sealing in of such volatiles. Whatever be the extent or the inter-relation extent as above set forth efficient results follow in the maintenance of the wood handle strength and utility. In the event of the unseasoned or green type of wood, it is desirable that the immersion be for the entire handle. For the seasoned wood, the ferrule covering portion at least should be immersed and for a slight distance therebeyond to avoid localization of fracture strain.

What is claimed and it is desired to secure by United States Letters Patent is:

The method of assembling a ferrule with a fibrous handle of the nature of wood, comprising heating a terminal portion of the handle in a bath of hot oil, whereby the fibrous cells of the handle are sufficiently filled to strengthen them toward retaining their original properties against collapse, inserting said terminal portion of the handle into a ferrule, then simultaneously bending said ferrule with the heated handle therein.
